UNITED STATES PATENT OFFICE.

EDWIN ROBINSON, OF CAMDEN, NEW JERSEY, ASSIGNOR TO M. W. LIPPER
& CO., OF PHILADELPHIA, PENNSYLVANIA.

DESIGN FOR TRIMMING.

SPECIFICATION forming part of Design No. 22,046, dated December 6, 1892.

Application filed November 3, 1892. Serial No. 450,913. Term of patent 3½ years.

To all whom it may concern:

Be it known that I, EDWIN ROBINSON, a citizen of the United States, residing in the city and county of Camden, State of New Jersey, 5 have invented and produced a new and original Design for Trimming, of which the following is a specification, reference being had to the accompanying drawing, forming part thereof.

10 The leading feature of my design for trimming is a head having loops on the borders thereof and a serpentine figure on the face of the head, whose bends alternate with said loops.

15 In the drawing, A designates a head on

whose borders are the loops B and on whose face is the serpentine figure C, the bends of the latter alternating with said loops, said figure extending in a double length and separated at the crowns. On the borders of the 20 head, within the bends of the figure C, are edgings D, which latter alternate on opposite borders of the head.

I claim—

25 The design for a trimming, substantially as described and shown.

EDWIN ROBINSON.
